UNITED STATES PATENT OFFICE

JURGEN SIEMSEN, OF CUSTER, MONTANA, ASSIGNOR OF ONE-HALF TO ANNA BERRY,
OF BILLINGS, MONTANA

GRAIN-CAR DOOR

Application filed March 8, 1928, Serial No. 260,095. Renewed May 29, 1929.

The invention relates to sliding doors in general, but more particularly to those which are designed primarily for use on railway cars, principally grain cars.

5 It is one object of the invention to provide a generally improved and simplified door embodying upper and lower sections connected with each other and mounted in such a manner that when the upper section is lowered, the entire door may be slid into a receiving sheath, whereas upon closing of the door across the lower portion of the frame, said upper section may be upwardly projected into sliding engagement with guides, to 10 close the upper portion of the frame.

A further object of the invention is to provide a simple and inexpensive, yet an efficient and durable construction for slidably mounting the upper door section upon the lower section and for raising and lowering said upper section as desired.

To slide the lower sections of the door to and from closed position, a co-acting rack bar and pinion are provided, the pinion being 25 carried by a shaft whose outer end may be rotated, for instance by a hand wheel, and it is a further aim to provide novel means for locking this shaft when the door is closed, thus locking said door in closed position.

30 With the foregoing in view, the invention resides in the novel subject matter hereinafter described and claimed, description being accomplished by reference to the accompanying drawings.

35 Fig. 1 is a side elevation showing the door projected across the door frame and illustrating the upper door section in lowered position.

Fig. 2 is a view similar to Fig. 1, partly 40 broken away and in section, showing the upper section of the door partly raised.

Fig. 3 is a vertical transverse section on line 3—3 of Fig. 2.

Fig. 4 is a similar view on line 4—4 of 45 Fig. 1.

Fig. 5 is a transverse sectional view on line 5—5 of Fig. 2, the door being omitted.

Fig. 6 is a sectional perspective view showing the upper and lower sections of the door 50 in juxtaposition.

Fig. 7 is an inner side elevation of the door, frame and door-receiving sheath.

Fig. 8 is a horizontal sectional view on line 8—8 of Fig. 7.

In the drawings above briefly described, the 55 preferred details of construction have been described and while these details will be herein specifically explained, it is to be understood that within the scope of the invention as claimed, variations may be made.

The numeral 9 denotes a door frame across whose lower end, a sill 10 extends, said sill being provided with a longitudinal door-guiding track 11 of channeled form. A door is provided for the frame 9, composed of a 60 lower rectangular section 12 and an upper rectangular section 13, section 13 being slidably carried by section 12 for vertical movement. A sheath 14 is provided at one side of the frame 9 to receive the door when the section 13 is lowered and both sections are bodily 65 slid to open position. At the side of the frame 9 opposite the sheath 14, a guideway 15 is provided to receive the outer end of the door when the latter is opened, and at both 70 sides of said frame, vertical guideways 16 are provided to receive the vertical edges of the door section 13 when the latter is slid upwardly, the lower ends of the guideways 16 being in a plane disposed at or slightly above 75 the upper edge of the door section 12.

A horizontal rack bar 17 is secured to the outer side of the door section 12 and meshes with a pinion 18 on a shaft 19 passing through one side wall 20 of the car equipped with the 80 improved door. To the outer side of this wall 20, a plate 21 is secured, having a bearing 22 for the shaft 19. Upon the outer end of this shaft, a hand wheel 23 is secured, said 85 wheel having a hub 24. The bearing 22 and the hub 24 are provided with notches 25—26 respectively, and the shaft 19 is formed with a transverse slot 27 with which the notches 25—26 align. When wheel 23 is turned to cause the pinion 18 and rack bar 17 to close 90 the door, the notches 25—26 and slot 27 register with each other as shown in Fig. 4, upon the final closing of said door. Then, a locking pin 28 is inserted through these notches 95 and the slot, thereby locking the door in closed 100 position.

position. This pin is preferably carried by a chain or the like 29 secured to the car and it may be held against unauthorized removal, by a seal, padlock or the like.

5 The door section 12 is provided at its vertical edges with outwardly projecting flanges 30 and the lower edge of this door section is preferably formed with a similar flange 31, which flanges perform reinforcing functions.

10 The rack bar 17 extends between the lower portions of the flanges 30 and is secured against the outer side of the door section 12, being also secured to said flanges. At the upper edge of the door, an upper horizontal bar 32 extends between the flanges 30 and is secured to them, said bar 32 being spaced outwardly from the door section 12, providing a slot 33.

15 A central pair of vertical bars 34, and two additional vertical bars 35, extend between and are secured to the upper and lower bars 32-17, all of these vertical bars being outwardly spaced from the door section 12. The bars 35 are provided with longitudinal channels 36 disposed toward the door section 12 and registering at their upper ends with notches 37 in the bar 32. The bars 34 are 20 preferably of angular cross section and one of these bars is provided at its inner portion with rack teeth 38.

25 The upper door section 13 is slidably received in the slot 33 so that it is freely slideable between the bar 32 and the door section 12, and between this section and the vertical bars 34-35, the vertical edges 39 of said section 13 being slidably engaged with the flanges 30, while the upper edge of said section 13 is provided with a lateral reinforcing flange 40. Secured to the outer side of section 13, are vertical reinforcing bars 41 constituting ribs which are slidably received in the notches 37 and channels 36, assisting not only in generally reinforcing the door section 13, but guiding its vertical movement. The bars 35 are formed with openings 42 and the bars or ribs 41 have similar openings 43, spaced apart vertically. When the openings 42-43 are in alinement with each other, locking pins 44 may be passed through them to hold the door section 13 in the desired position. The pins 44 are preferably suspended by chains or the like 45 to prevent loss.

30 Lying against the outer side of the door section 13 is a pinion 46 having an inwardly projecting journal 47 rotatably received in an opening 48 in said door section. This pinion is also provided with an outwardly projecting operating shaft 49 with which a hand crank or the like 50 may be engaged. This 35 pinion meshes with the rack teeth 38 and rotation of said pinion serves to either raise or lower the upper door section 13, as occasion may demand. Stops 51 may be provided to limit the ascent of this door section, by 40 striking the bar 32. Attention is invited to

70 the fact that the outer side of the pinion 46 lies against the inner sides of the bars 34, the latter being disposed at opposite sides of the shaft 49. Thus, these bars 34, in addition to forming parts of a rigid frame structure for the lower door section 12, serve to hold the pinion 46 in a vertical position, and when the construction herein disclosed is followed, said bars also prevent withdrawal of the journal 47 from the opening 48.

75 The parts shown at 52 in Fig. 1, are end portions of a bar which is used to brace the door against outward bulging when in use. The ends of this bar are receivable in appropriate keepers 53 carried by the sides of the door frame 9. Other keepers 54 are 80 preferably provided at the upper end of the frame to merely carry the bar 52 when it is not in use.

85 The door may be easily projected from the sheath 14 and only after such projection, can the upper door section 13 be raised. When this section is raised, it locks the entire door against horizontal sliding, forming somewhat of a safeguard, even if the hand wheel 23 and shaft 19 are not locked. The section 13 is held in raised position by the pins 44 and upon removal of these pins, the pinion 46 may be rotated to lower said section 13 to any desired extent. When it is 90 completely lowered, operation of the hand wheel 23 will retract the entire door into the sheath 14.

95 Excellent results are obtainable from the general construction shown and described 100 and it is therefore preferably followed. However, as above stated, variations may be made within the scope of the invention as claimed.

105 Preferably, I provide a pin 44^a normally held in a retainer 44^b and connected with a loss-preventing chain 44^c. When the door section 13 is raised, pinion 46 may be temporarily held against rotation by engaging pin 44^a with the teeth of said pinion thereby 110 facilitating the insertion of the pins 44.

I claim:—

115 1. A door comprising a lower slideable section of rectangular form and provided at its vertical edges with laterally projecting flanges, an upper horizontal bar extending between and secured to the upper ends of said flanges, said bar being outwardly spaced from said lower door section, a lower horizontal bar extending between and secured to said flanges, vertical bars extending between and secured to said upper and lower horizontal bars, said vertical bars being outwardly spaced from said lower door section, and an upper rectangular door section slidably received between said lower section and said upper and vertical bars, the vertical edges of said upper section being slidably engaged with said flanges.

120 2. A door comprising a lower slideable sec-

130

tion of rectangular form and provided at its vertical edges with laterally projecting flanges, an upper horizontal bar extending between and secured to the upper ends of said flanges, said bar being outwardly spaced from said lower door section, a lower horizontal bar extending between and secured to said flanges, vertical bars extending between and secured to said upper and lower horizontal bars, said vertical bars being outwardly spaced from said lower door section and having longitudinal channels disposed toward the same, and an upper rectangular door section slidably received between said lower section and said upper and vertical bars, said upper door section having vertical ribs slidable in said channels.

3. A structure as specified in claim 2, said vertical bars and ribs having openings for registration when said upper door section is raised, and pins insertible through said openings.

4. A door comprising a lower slidable section of rectangular form and provided at its vertical edges with laterally projecting flanges, an upper horizontal bar extending between and secured to the upper ends of said flanges, said bar being outwardly spaced from said lower door section, a lower horizontal bar extending between and secured to said flanges, a pair of vertical bars extending between and secured to said upper and lower horizontal bars, said vertical bars being disposed in closely spaced relation with each other and spaced outwardly from said lower door section, one of said vertical bars having rack teeth, an upper rectangular door section slidably received between said upper and said vertical bars and having its edges slidably engaged with said flanges, and a pinion disposed at the outer side of said upper door section, said pinion being provided with a journal received in an opening in said upper door section and with an operating shaft projecting outwardly between said bars, said bars lying against the outer side of said pinion.

5. A door comprising a lower slidable section of rectangular form and provided at its vertical edges with laterally projecting flanges, an upper horizontal bar extending between and secured to the upper ends of said flanges, said bar being outwardly spaced from said lower door section, a lower horizontal bar extending between and secured to said flanges, vertical bars extending between and secured to said upper and lower horizontal bars, said vertical bars being outwardly spaced from said lower door section, two of said vertical bars being disposed in closely spaced relation, the other bars having longitudinal channels disposed toward said lower door section; an upper rectangular door section slidably received between said lower door section and said upper and ver-

tical bars, said upper section having vertical ribs slideable in the aforesaid channels, and a pinion between said closely spaced vertical bars and said upper door section, one of these bars having rack teeth meshing with said pinion, said pinion being provided with an inwardly projecting journal received in an opening in said upper door section and with an operating shaft projecting outwardly between said closely spaced vertical bars.

In testimony whereof I have hereunto affixed my signature.

JURGEN SIEMSEN.
